(57) **CLAIM**

The ornamental design for a candle holder with bark-like exterior, as shown and described.

DESCRIPTION

FIG. 1 is a front, top perspective view of a candle holder with bark-like exterior showing my new design.

FIG. 2 is a front elevation view.

FIG. 3 is a left elevation view.

FIG. 4 is a rear elevation view.

FIG. 5 is a right elevation view.

FIG. 6 is a top plan view; and,

FIG. 7 is a cross-sectional view taken along line 7-7 in FIG. 6.

The broken lines shown in FIG. 1 are for the purpose of illustrating environment that forms no part of the claimed design.

1 Claim, 2 Drawing Sheets
